(57) **CLAIM**

The ornamental design for a computer display system or portion thereof showing an animated graphical user interface as shown and described.

DESCRIPTION

The file of this patent contains at least one figure executed in color. Copies of this patent in color will be provided by the Office upon request and payment of the necessary fee.

FIG. 1 is a front view of a computer display system or portion thereof showing a first image of an animated graphical user interface showing the claimed design;

FIG. 2 is a second image thereof;

FIG. 3 is a third image thereof;

FIG. 4 is a fourth image thereof, and,

FIG. 5 is a fifth image thereof.

The peripheral broken lines in the figures show the computer display system or portion thereof, and form no part of the claimed design.

The other broken lines in the figures show a three dimensional environment within a field of view of the user that forms no part of the claimed design.

(Continued)

The appearance of the animated image sequentially transitions between the images shown in FIGS. 1-5. The process or period in which one image transitions to another forms no part of the claimed design.
